UNITED STATES PATENT OFFICE

164,779

HOSPITAL CART

Anna Koenig, Chicago, Ill., assignor to Debs Hospital Supplies, Inc., Chicago, Ill., a corporation of Illinois

Application August 30, 1949, Serial No. 4,768

Term of patent 14 years

(Cl. D14—3)

To all whom it may concern:

Be it known that I, Anna Koenig, a citizen of the United States, residing at Chicago, Cook County, State of Illinois, have invented a new, original, and ornamental Design for Hospital Cart, of which the following is a specification, reference being had to the accompanying drawing, forming a part hereof.

Fig. 1 is a perspective view of a hospital cart, showing the design of my invention;

Fig. 2 is a front elevation thereof; and

Fig. 3 is a top plan view.

The rear of the cart is plain and the opposite end similar to that shown in Fig. 1.

I claim:

The ornamental design for a hospital cart, as shown and described.

ANNA KOENIG.
